UNITED STATES PATENT OFFICE.

FRANK F. SMITH, OF NEWARK, NEW JERSEY.

DOOR-LOCK.

1,117,457.

Specification of Letters Patent. Patented Nov. 17, 1914.

Application filed November 22, 1912. Serial No. 732,934.

To all whom it may concern:

Be it known that I, FRANK F. SMITH, a citizen of the United States, residing at Newark, in the county of Essex and State of New Jersey, have invented certain new and useful Improvements in Door-Locks, of which the following is a specification:

My present invention relates to a door lock and is especially adapted to be used in connection with fireproof doors and buildings and is of the type wherein, in the event of a panic, the door automatically opens when my devices are pushed against.

The invention resides in the special combination, construction and adaptation of the parts and will be readily understood from the following description in connection with the drawings which, however, show only one of the preferred forms which the invention is adapted to take, wherein the parts of the device tend by gravity into locking position. It is generally recognized that because gravity is always operative, a gravity operating construction is ideal for actuating fireproof doors and windows into closed position and locking them. It will be noted that the door lock herein illustrated and described embodies the gravity principle.

In the drawings, Figure 1 is a front elevation of a pair of doors provided with my lock; Fig. 2 is a vertical section on the line 2-2 in Fig. 1 looking in the direction of the arrows; Fig. 3 is a horizontal section on the line 3-3 in Fig. 1 looking downwardly with the doors shown closed in the full lines and swung open in the dotted lines; Fig. 4 is a horizontal section on the line 4-4 in Fig. 9; Fig. 5 is a horizontal section on the line 5-5 in Fig. 9; Fig. 6 is a horizontal section on the line 6-6 in Fig. 9; Fig. 7 is a plan of one of the socket members; Fig. 8 is a view similar to Fig. 2 but on a larger scale and with the housings shown in the vertical section; and Fig. 9 is the same as Fig. 8 except that the parts have been operated from their normal locked position of Fig. 8 into their unlocked position due to the bar 10 having been pushed toward the door.

I will now describe the specific devices of the drawings, reserving it to the claims to point out the novel features and to define the scope of the invention, it being understood that the claims will be given the due range of equivalents to which they may be entitled in view of the art.

1 is the door frame, 2, 2 the doors hinged to the frame at 3. I have shown double doors but it will immediately be evident that my lock is applicable in the same way to 60 single doors.

4 is an upright rod movable vertically through a slotted housing 5 on the door.

6 is a lever projecting through a slot into the housing to which it is intermediately pivoted at 7. The lever within the housing has a cam slot 8 containing a pin 9 on the rod 4. When the external end of the lever 6 is pushed toward the door, its end within the housing lifts the rod 4 as shown in Fig. 70 9; and vice versa, when no one is pushing against the lever, then the weight of the rod 4 and the connected parts returns the lever 6 automatically into its original or normal position shown in Fig. 8. 75

The free end of the lever 6 is extended laterally so as to be necessarily pushed against in the event of a crowd surging against the door by providing a horizontal handle or bar 10 secured at one end to the lever 6 and at the other to an arm 11 (Fig. 1) depending from a pivot on the door.

12 and 13 are a pair of geared members, one of which constitutes a latch bolt each rotatably supported on pins 14 and 15 supported by the sides of a housing 16 attached to the door. 85

Equivalent parts are shown duplicated on the lower part of the door, and have been correspondingly designated 112, 113, 90 114, 115 and 116.

Each part 12 and 112 has a sector portion *a* constituting a bolt and receivable into a corresponding recess in the door frame consisting of the cavity of a socket member 95 17 (see same in the plan view Fig. 7) which is screwed to the door frame. In the case illustrated, there are two of these socket members, one above and the other below located in the floor or threshold. 100

18 and 19 are links connecting the upper and lower ends of the rod 4 with the gear members 13 and 113 respectively, whereby from the motion of said rod these gear members operate the related gear members 12 105 and 112 simultaneously either into locking position or out of it.

The operation of the illustrated devices will be apparent from what has already been said, it being sufficient to repeat that 110 the weight of the rod 4 and the connected parts when unopposed causes them to drop.

into a lower position in which the bolt parts 12 and 112 are rotated into locking position as shown in Fig. 8; whereas the same bolt parts are withdrawn and the doors unlocked 5 by pressing the handle bar 10 toward the door as shown in Fig. 9.

What I claim is:

1. The combination with a door and its frame, a rod or bar extending substantially 10 from top to bottom of the door, means for lifting the said rod, comprising a swinging bar and a connection between said bar and said means, the said rod being mounted to gravitate to its normal position after being 15 lifted, bolts at the upper and lower ends of said rod, sockets for said bolts, and positive operative connections between said bolts and rod whereby the movement of the rod by gravity causes both bolts to enter 20 their sockets and the lifting of the rod causes the same to be withdrawn therefrom.
2. The combination of a bar mounted to move up and down, means for raising the said bar, the said bar being mounted to 25 turn to its normal position by gravity, a plurality of bolts, sockets for the said bolts and a connection between a bolt and said bar whereby movement of the bar downward causes the said bolt to move upward 30 in a direction at an angle to the line of movement of said bar into its socket, and the construction and arrangement being such that the gravity of the bar tends to cause both bolts to enter their sockets.
3. The combination with a door and its frame, a rod or bar adapted to be mounted 35 on the door, means for moving the said rod from its normal position, comprising a swinging bar and a connection between said 40 bar and said means, bolts non-integral with said rod at the ends of said rod, sockets for said bolts, and operative connections between said bolts and rod whereby the movement of the rod in one direction causes both 45 bolts to move in opposite directions to enter or withdraw from their sockets.

4. In a device of the character described, the combination of a plurality of bolts, a member mounted to move alternately to and 50 from the said bolts, a pivoted connecting member between each of said bolts and the said member which moves to and from them, and a connection between the said member and each of the bolts whereby to 55 and from movement of the said member imparts movement to one of the bolts in the same direction and to the other bolt in an opposite direction.

5. In a device of the character described, 60 the combination of an upper and a lower bolt, a connecting member extending from one to the other, means for moving the said connecting member bodily alternately to and from each of the said bolts, comprising 65 a swinging bar and a connection between

said bar and said means, and means for causing the movement of the said connecting member in one direction to simultaneously operate both bolts in opposite directions.

70

6. In a device of the character described, the combination of an upper and a lower bolt, a connecting member extending from one to the other, means for moving the said connecting member bodily alternately to 75 and from each of the said bolts, comprising a swinging bar and a connection between said bar and said means, and means for causing the movement of the said connecting member in one direction to operate both 80 bolts and move them to a locked position, and whereby the movement of said connecting member in the opposite direction will operate both bolts to move them to an unlocked position.

85

7. In a device of the character described, the combination of a plurality of bolts, socket members adapted to receive said bolts, a member extending from one bolt to the other and adapted to operate both bolts, 90 comprising a swinging bar and a connection between said bar and said means, means for causing movement of said member in one direction to move both bolts into their respective sockets and for causing movement 95 of said member in the opposite direction to move both bolts from their sockets, and means for moving the said member.

8. In a device of the character described, the combination of a plurality of bolts, 100 sockets adapted to be engaged by said bolts, a member mounted to be moved to and from said bolts and to cause the same to engage and disengage their respective sockets by said movement, means for moving the said 105 member, comprising a swinging bar and a connection between said bar and said means, and connections between the said member and the bolts whereby the bolts are operated in the manner specified, and are held 110 against movement into and out of their sockets by said member.

9. In a device of the character described, the combination of a bolt, a socket adapted to be engaged by said bolt, a member 115 mounted to be moved to and from said bolt and to cause the same to engage and disengage its socket by said movement, means for moving the said member, and a connection between the said member and the bolt 120 whereby the bolt is operated as above stated, and held in engagement with its socket by the gravity of said member.

10. The combination of a bar mounted to move up and down, means for raising the 125 said bar, the said bar being mounted to return to its normal position by gravity, a plurality of bolts, sockets for the said bolts and a connection between one of the said bolts and the bar whereby vertical move- 130

ment of the bar causes the said bolt to move to and from its socket at an angle to the line of movement of said bar, and whereby when the door is closed contact between the said bolt and its socket imparting angular movement to the bolt causes the bar to move vertically.

11. In a device of the character described, the combination with a door and its frame 10 and a suitable socket in the frame adjacent to the door, of a bolt carried by the door and adapted to engage said socket, said bolt being mounted to move into and out of its socket on a line at less than a right angle to 15 the line of movement of the door, a bar mounted on said door to move angularly with respect to the movement of the door and the bolt, a connection between the said bar and bolt whereby movement of the former causes the latter to move into and out 20 of its socket and movement of the latter causes the former to move to its unlocking position, and additional means for moving the said bar to cause it to unlock the said 25 bolt.

12. In a device of the character described, the combination with a door and its frame and a suitable socket in the frame adjacent to the door, of a bolt carried by the door 30 and adapted to engage said socket, said bolt being mounted to move into and out of its socket on a line at less than a right angle to the line of movement of the door, a bar mounted on said door to move angularly 35 with respect to the movement of the door and the bolt, a connection between the said bar and bolt whereby movement of the former causes the latter to move into and out of its socket and movement of the latter 40 causes the former to move to its unlocking position, the construction and arrangement being such that when the door is closed the bolt striking the frame of the door adjacent to its socket will be moved by the im-

pact to its unlocked position and will also 45 move the bar to unlocking position, and the movement of the bar to unlock the bolt will cause the said bolt to move at an angle thereto out of its socket.

13. The combination with a door and its 50 frame, of a locking and unlocking device comprising a socket in the frame having a side inclined inwardly from a point adjacent to the door, a bolt adapted to engage said socket and having a portion adapted 55 to come in contact with said inclined surface, means for moving the said bolt into and out of engagement with the socket, the construction and arrangement being such that when the bolt moves from engagement 60 with the socket the portion which comes in contact with the inclined surface moves in a direction approximately parallel therewith.

14. The combination with a door and its 65 frame, of a locking and unlocking device comprising a socket having a portion inclined inwardly away from the door, a bolt having a portion mounted to move approximately parallel with said inclined portion 70 and means extending away from said socket for moving the bolt into and out of engagement therewith, a connection between said means and the bolt, the construction and arrangement being such that the said bolt- 75 operating means moves at an angle to the movement of the bolt into and out of the socket and the bolt is adapted to strike the frame of the door when the door is closed and move said means to an unlocking position by a movement approximately parallel 80 with the line of movement of the door.

In testimony whereof I affix my signature in presence of two witnesses.

FRANK F. SMITH.
